US00D978855S

(12) **United States Design Patent** (10) **Patent No.:** **US D978,855 S**
(45) **Date of Patent:** **** Feb. 21, 2023**

(54) **SECURITY DEVICE WITH DOCKING STATION**

(71) Applicant: **Amazon Technologies, Inc.**, Seattle, WA (US)

(72) Inventors: **Michael Edward James Paterson**, Lafayette, CA (US); **Giles David Matthew McWilliam**, San Francisco, CA (US); **Jordan Anthony Metzner**, Los Angeles, CA (US); **James Siminoff**, Pacific Palisades, CA (US); **Benjamin Wild**, Seattle, WA (US); **Wen-Yo Lu**, Pasadena, CA (US); **Mark Siminoff**, Mountain View, CA (US)

(73) Assignee: **Amazon Technologies, Inc.**, Seattle, WA (US)

(**) Term: **15 Years**

(21) Appl. No.: **29/751,614**

(22) Filed: **Sep. 22, 2020**

(51) LOC (14) Cl. **12-06**

(52) U.S. Cl.

USPC **D14/300**; D10/65; D10/75

(57) **CLAIM**

The ornamental design for a security device with docking station, as shown and described.

DESCRIPTION

FIG. 1 is a top, front, right-side perspective view of a security device with docking station;

FIG. 2 is a bottom, back, right-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the security device with docking station that form no part of the claimed design.

1 Claim, 8 Drawing Sheets
